Primary Examiner — Tracey J Bell*Assistant Examiner* — Jillian Mazzola(74) Attorney, Agent, or Firm — Kirton McConkie; Brian Tucker(57) CLAIM

The ornamental design for a bag, as shown and described.

DESCRIPTION

FIG. 1 is a front perspective view of a bag showing the claimed design;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof; and,

FIG. 7 is a bottom plan view thereof.

The broken lines in the figures depict stitching that forms no part of the claimed design.

1 Claim, 5 Drawing Sheets(56)
